UNITED STATES PATENT OFFICE.

EDWIN F. RICHARDSON, OF BOSTON, MASSACHUSETTS.

APPARATUS FOR FASTENING FIRE-HOSE TO LADDERS.

SPECIFICATION forming part of Letters Patent No. 530,656, dated December 11, 1894.

Application filed September 12, 1894. Serial No. 522,814. (No model.)

To all whom it may concern:

Be it known that I, EDWIN F. RICHARDSON, of Boston, in the county of Suffolk and State of Massachusetts, have invented a new and 5 useful Improvement in Apparatus for Fastening Fire-Hose to Ladders, of which the following, taken in connection with the accompanying drawings, is a specification.

The method now in general use by firemen 10 for fastening hose to ladders, is by a rope with a ring and hook attached to the ends and carried in the fireman's belt. This method is unsatisfactory in that delay is frequently caused by the fireman's not having 15 his rope with him, and in that the rope does not hold the hose securely and tightly in position, and can only be fastened with difficulty.

My invention consists of a rung or rungs, 20 preferably of metal, so adjusted and designed as to revolve in the sides of the ladder, and with a bend or depression in the rung so as partially to receive the hose, together with a flexible fastening attached at one side of said bend or depression, and so adjusted and arranged 25 that it can be attached to the rung at the other side of said bend or depression after being passed over and around the hose, thereby securing the hose tightly and firmly in position, all substantially as shown. As 30 the hose presses down it causes the rung to revolve, thereby bringing the flexible fastening tightly against the hose and holding it more firmly in position. This device for holding hose may be made a part of the ladder, and always will be with it and ready for 35 use. One or more of these bends or depressions with a flexible fastening for each, may be placed in the same rung so as to support a single line of hose or several lines of hose 40 at the same time.

In making the rung, I have used a chain, and a hook for securing the chain, as the accompanying drawings show, and I consider a chain and hook best adapted to the purpose, but I do not limit my invention to the use 45 of such chain and hook, but use them as one of several well known flexible fastenings adapted to securing the hose to the rung.

In the accompanying drawings, Figure 1 shows the rung not in use. Fig. 2 shows the 50 rung holding a single line of hose in position. Fig. 3 shows a rung for three lines of hose, one line only being in position.

In each of the drawings A. represents a line of hose; B., the rung, and C. the chain. 55

What I claim as new, and desire to secure by Letters Patent, is—

A ladder rung made and adjusted so as to revolve in the sides of the ladder with a bend or depression in said rung, into which a hose 60 can partially enter, with a flexible fastening attached at one side of such bend or depression, and so adjusted and arranged that it can be attached to the rung at the other side of said bend or depression after being passed 65 over and around the hose, thereby holding it firmly and securely in position substantially as set forth.

In testimony whereof I, EDWIN F. RICHARDSON, have signed my name to this specification, in the presence of two subscribing witnesses, on this 8th day of September, A. D. 70 1894.

EDWIN F. RICHARDSON.
